UNITED STATES PATENT OFFICE.

CHRISTIAN G. FILZER, OF ERIE, PENNSYLVANIA.

HYDROCARBON-TORCH.

1,204,968.

Specification of Letters Patent.

Patented Nov. 14, 1916.

Application filed January 19, 1916. Serial No. 72,976.

To all whom it may concern:

Be it known that I, CHRISTIAN G. FILZER, a citizen of the United States, residing at Erie, in the county of Erie and State of Pennsylvania, have invented certain new and useful Improvements in Hydrocarbon-Torches; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to hydro-carbon torches, and particularly to that type of such torches which are adapted to generate combustive gas from kerosene oil.

The objects of the present invention are to provide means to clean the tubular passages through the generator portion of my torch, and to provide suitable means for supplying burning fluid to the starting cup.

The features of my invention will be explained and pointed out hereinafter, and are illustrated in the accompanying drawings, in which:

Figure 1, is a side elevation of a hydro-carbon torch embodying my invention. Fig. 2, is a top or plan view of the same. Fig. 3, is a vertical section of a portion of the same on the line $x-x$ in Fig. 1. Fig. 4, is a front end elevation of the nozzle member of my improved torch. Fig. 5, is a longitudinal section of the same on the line $y-y$ in Fig. 4. Fig. 6, is a top or plan view of the same, with portions thereof broken away. Fig. 7, is an enlarged view of the strainer member of my invention. Fig. 8, is an end view of the same. Fig. 9, is a longitudinal, vertical section of the ball-check of my invention. Fig. 10, is a bottom view of a portion of the initial starting cup, showing the latch mechanism thereof.

In these drawings A, indicates the fuel reservoir; A', the handle thereon; B, the nozzle; B', the helically coiled pipe within the nozzle B; B², the starting-cup; C, the hinged joint, and C', the air pump, all of which are shown and described in my co-pending application, Serial No. 51,635, filed September 20, 1915, and form no part of the present invention.

In the present invention, the tubular passage from the reservoir A is upward through the valve-seat D, to the needle-valve D',

which is controlled by the hand-wheel D², in the usual manner. Upon the valve seat D, I place a ball-valve D³, which is provided with a stem d.

In the valve casing E, I secure a bushing E', which is provided with internal threads e, and with a stuffing-box e', of usual construction. Within the bushing E', I place a hollow shaft E², which is provided with threads which engage the internal threads e, in the bushing E'. The shaft E², is provided with an internal shoulder e², which is adapted to engage a head d', or its equivalent, on the upper end of the stem d, so that the ball-stem d, cannot be withdrawn out of the shaft E². Within the shaft E², I place an adjusting-screw E³, which can be raised or lowered in the shaft E², so as to limit the vertical movement of the ball-stem d, in the hollow shaft E². Upon the shaft E², I place a thumb-wheel E⁴, by means of which the hollow-shaft E², may be lowered through the bushing E', sufficiently to permit the ball D³, to seat upon the valve-seat D, so as to act as a check-valve to prevent the backward flow of fuel oil therethrough.

If it should be desired to prevent the ball D³, from being raised off of its seat, the hollow shaft E², can be screwed down until the end of the screw E³, engages the upper end of the ball-stem d, which will thereby prevent the ball D³, from leaving its seat, and it may also be desirable, as hereinafter pointed out, of unscrewing the shaft E², sufficiently so that the internal shoulder e², will lift the ball off of its seat. From the needle-valve D', the tubular passage leads through the hinged joint C, and helically coiled tube B', to the gas-jet tube F, as shown and described in my beforementioned application. In this jet-tube F, I place a strainer, (see Figs. 7 and 8) which is composed of a stem G, having thereon a plurality of disks of screening material G', of wire gauze or other suitable material, of sufficient diameter to fit the interior of the jet tube F, said screening material being held in place on the stem G by means of washers G², which are provided with radial slots g.

The stem G, is preferably flattened at g', which flattened portion prevents the washer G², from moving away from the disks of screen material. The stem G, is also provided with a head g², to retain the screen material on the stem G. When it is desired to replace the screen material on the stem G,

the washer G^2 , is turned so that the slot g , will receive the flattened portion g' , of the stem thereinto when the washer G^2 , can be removed, and the screen material removed 5 as may be desired. The stem G , projects slightly out of the rear end of the jet tube, so that it may be gripped by a pair of pliers for the purpose of withdrawing the strainer from the tube.

10 For closing the rear end of the jet tube F , I provide a screw plug F' , which has a central longitudinal hole f , therein to receive the projecting end of the strainer-stem G , said hole not extending entirely through the 15 screw-plug F' . The jet tube F , is provided with a jet opening f' , and with a lateral opening f^2 , just back of the strainer material G' , therein. This lateral opening f^2 , is provided with a needle-valve H , which 20 has a thumb wheel h , by which the same may be operated.

From the valve H , a tube H' , leads into the rear portion of the nozzle shell B , so 25 that when the valve H , is opened, combustion material will freely flow from the jet tube F , into the nozzle shell B , for the purpose of cleaning out dirt which may have lodged in the jet tube F , back of the strainer G : also liquid fuel may be permitted to flow 30 out of the tube H' , to supply the starting-cup B^2 . Another part of my invention consists in providing a tubular connection J , (see Fig. 5) which communicates with the front coil of the helically coiled tube B' , 35 and leads backwardly through the tube J' , needle-valve J^2 , and nipple J^3 , into the nozzle shell B , so that by opening the needle valve J^2 , liquid fuel can be allowed to flow 40 into said shell and thence into the starting-cup B^2 , as desired. This will also cause any dirt in the coil B' , to be washed out. I provide the needle valve J^2 , with means J^4 , for 45 operating it. For cleaning the jet orifice f' , in the jet tube F , I provide a short rod K , (see Fig. 1) which for convenience I attach 50 to a screw plug K' , secured in the upper end of the handle A' , and in the lower end of the rod K , I provide a short wire k of suitable size for inserting into the opening 55 f' , to clean out any dirt which may lodge therein; being placed in the handle A' , for safe keeping, this cleaner is always at hand when needed. The starting-cup B^2 , shown 60 herein, is similar to that shown in my aforementioned application, being pivoted at its rear end upon the post L , and is provided with an extinguishing plate L' , also pivoted on said post. The front ends of the cup B^2 , and plate L' , are provided with perforated 65 ears b and l , said ears being provided with

slots as shown in Fig. 10. The ear b , on the cup B^2 , is counter sunk on its lower side so that when the ear b , embraces the screw M , the counter-sink will fall down and embrace the head of said screw, and when the extinguishing plate L' , is closed as shown in Figs. 1 and 4, the ear b , cannot be raised upward, and the head of the screw M , being in the counter-sink on the under side of the ear b , prevents the cup from being disengaged from the screw M . On the side of the cup B^2 , I place a weighted latch-lever N , which engages the plate L' , to prevent said plate from being accidentally opened, so that when it is desired to disengage the 70 cup ear b , from the supporting screw M , the latch lever N , must be operated and the extinguishing plate L' , opened, when the front end of the starting-cup can be raised sufficiently to permit the counter-sink on the 75 under-side of the ear b , to be disengaged from the head of the supporting screw M .

Having thus fully shown and described the improvements which constitute my present invention, what I claim as new and desire to secure by Letters-Patent is:

1. In a device of the class described, a gas-jet tube having a jet opening in the point thereof, and a lateral valve-controlled opening, and a strainer member in said jet tube 90 between the jet opening and the lateral valve-controlled opening.

2. In a device of the class described, a torch nozzle shell, a helically coiled fuel conveying tube therein, a tubular nipple secured in said nozzle shell and a tubular valve-controlled passage leading from one of the coils of said coiled tube to said nipple, whereby fuel may be discharged into said shell from said coiled tube when desired. 100

3. In a device of the class described, a torch nozzle, a starting-cup thereunder, an extinguishing plate to cover said cup, a common pivot supporting the rear ends of said cup and plate, a supporting post secured under the front end of said nozzle, a head thereon, a laterally slotted ear on said starting-cup counter-sunk on the under surface thereof to receive the head of said supporting post, a laterally slotted ear on said 110 extinguishing plate adapted to engage said supporting post and prevent the ear on the starting-cup from being disengaged from said supporting post, and a weighted latch lever on said starting-cup to maintain said extinguishing plate from being accidentally opened. 115

In testimony whereof I affix my signature.

CHRISTIAN G. FILZER.
